UNITED STATES PATENT OFFICE.

RENÉ BOHN, OF MANNHEIM, GERMANY, ASSIGNOR TO THE BADISCHE ANILIN & SODA FABRIK, OF LUDWIGSHAFEN-ON-THE-RHINE, GERMANY, A CORPORATION OF BADEN.

ANTHRACENE DYE.

SPECIFICATION forming part of Letters Patent No. 767,259, dated August 9, 1904.

Application filed April 29, 1904. Serial No. 205,586. (No specimens.)

To all whom it may concern:

Be it known that I, RENÉ BOHN, doctor of philosophy and chemist, a citizen of the Swiss Republic, residing at Mannheim, in the Grand Duchy of Baden, German Empire, have invented new and useful Improvements in Anthracene Dyes, of which the following is a specification.

In the specifications of Letters Patent Nos. 682,523 and 739,145 there is described the production of blue and yellow coloring-matters which I have obtained from beta-amido-anthraquinon by oxidation or fusion with caustic potash. These coloring-matters are known under the names "indanthrene" and "flavanthrene" and can only be used for dyeing and printing when a special process is employed.

I have now discovered that by melting di-amido-anthraquinon bodies with caustic potash coloring-matters can be obtained which have bluish-gray to reddish-gray shades and which can be employed for dyeing and printing by means of the same special process. The di-amido-anthraquinon bodies which I have up to the present found to answer are the 1.5, 1.8, 1.3, 2.6, and 2.7 di-amido-anthraquinons and also their sulfo-acids.

The coloring-matters obtained from the di-amido-anthraquinon sulfo-acids are when dry brownish-black powders and possess the same general characteristics as do the coloring-matters obtainable from the unsulfonated di-amido-anthraquinons. They all possess (with the exception of their shades) similar properties to indanthrene and probably belong to the same class of chemical compounds. In particular they possess the same extraordinary degree of fastness, which exceeds that of all other classes of coloring-matters.

The following examples will serve to further illustrate the nature of my invention, which, however, is not limited to these examples. The parts are by weight.

Example 1: Melt three hundred (300) parts of caustic potash and while at a temperature of about one hundred and eighty degrees centigrade (180° C.) introduce slowly one hun-

dred (100) parts of 1.5-diamido-anthraquinon. After the addition heat for one (1) hour at a temperature of from one hundred and ninety 50 to two hundred degrees centigrade (190° – 200° C.) and pour into water and boil and filter. The other di-amido-anthraquinons, either singly or in admixture with one another, can be treated in a similar manner. 55

Example 2: Melt three hundred and fifty (350) parts of caustic potash and while at a temperature of about one hundred and seventy degrees centigrade (170° C.) introduce slowly, while stirring, one hundred (100) parts of the 60 sodium salt of 1.5 - di-amido - anthraquinon sulfo - acid. During the addition the melt froths up. When the frothing is finished, heat for another hour and a half ($1\frac{1}{2}$) at a temperature of from one hundred and ninety-five 65 to two hundred degrees centigrade, (195° – 200° C.) introduce the melt into water, boil, filter, and wash the precipitate. If instead of the sulfo-acid used in this example sulfo-acids of other di-amido-anthraquinons be employed, the method of procedure remains the 70 same.

The coloring-matters form gray-red to gray-olive pastes; but when dry they are black powders which are practically insoluble in the 75 usual solvents. They dissolve in sulfuric acid, the solutions being olive brown. With reducing agents, such as sodium hydrosulfite in the presence of caustic soda, they give brown vats which dye vegetable fiber substantively 80 yielding brown shades which when exposed to the air turn gray.

The coloring-matters obtained from 1.5 and 1.8 di-amido-anthraquinons yield reddish-gray shades, while those from the 1.3, 2.6, and 2.7 85 derivatives give greenish-gray shades.

Now what I claim is—

1. As new articles of manufacture, the gray coloring-matters such as can be obtained from di-amido - anthraquinon bodies, which, when 90 dry, are brown to black powders practically insoluble in water, which give brown solutions with caustic soda and sodium hydrosulfite, which solutions dye cotton brownish

shades, which shades become gray when exposed to the air.

2. As a new article of manufacture, the gray coloring-matter such as can be obtained from 5 1.5-diamido-anthraquinon, which, when dry, is a brownish-black powder practically insoluble in water, which gives a brown solution with caustic soda and sodium hydrosulfite, which solution dyes cotton brown shades,

which shades become gray when exposed to the air.

In testimony whereof I have hereunto set my hand in the presence of two subscribing witnesses.

RENÉ BOHN.
